UNITED STATES PATENT OFFICE.

HALVOR H. LYCHE, OF CHICAGO, ILLINOIS, ASSIGNOR TO THE ODIN COMPANY, OF CHICAGO, ILLINOIS, A CORPORATION OF ILLINOIS.

WASHING-MACHINE.

1,209,983.

Specification of Letters Patent. Patented Dec. 26, 1916.

Application filed May 20, 1916. Serial No. 98,821.

To all whom it may concern:

Be it known that I, HALVOR H. LYCHE, a citizen of the United States, residing at Chicago, in the county of Cook and State of Illinois, have invented certain new and useful Improvements in Washing-Machines, of which the following is a full, clear, and exact specification, as will enable others skilled in the art to make and use the same, reference being had to the accompanying drawings, forming a part of the specification.

My invention relates to washing machines in which a rotary barrel is provided, and has for one of its objects to improve the construction and increase the efficiency and utility of machines of this character. A further object of the invention is to produce a machine in which the lifting of the customary heavy cover and barrel section preparatory to the insertion or removal of the clothes is obviated, and wherein a portion of this cover serves as a retaining apron during the passage of the clothing from the barrel to the wringer. A still further object is the provision of means in a machine of this character for preventing articles of clothing, and the like, from falling back into the space between the barrel and the body of the machine during insertion into and removal of the clothes out of the barrel.

These, together with such other objects as may hereinafter appear, or are incident to my invention, I attain by means of the construction illustrated in preferred form in the accompanying drawings, wherein:—

Figure 1 represents a plan view of my improved washing machine;

Figure 2 is a side elevation of the same, a portion of the body wall and cover being broken away to better disclose interior parts;

Figure 3 is a detail view illustrating the means of support for the cover when removed to its retracted position.

Figure 4 is a vertical section through the upper portion of the machine;

Figures 5 and 6 represent plan and sectional views of the cover, respectively;

Figures 7 and 8 represent a view in top plan and side elevation of the closure for the cover port, respectively;

Figures 9 and 10 are sectional views respectively taken along the line 9—9 and 10—10 in Figures 6 and 8.

Corresponding and like parts are referred to in the following description and

designated in the views of the drawings by the same reference characters.

Referring to the figures, the numeral 10 indicates the body of the machine supported on the legs 11, and within the body is mounted the rotary perforate barrel or cylinder 12. Attached to the front end 13 of the body is a gear casing 14 designed to enclose the motor and gearing which impart reverse rotary movement to the barrel, and upon this casing 14 is mounted the wringer 15 adjacent the open top of the body 10, which opening is large enough to permit the passage therethrough of the barrel when the interior of the body requires clean-

ing. Extending over this opening is a cover 16 having downwardly bent side margins 17 and a similarly bent end marginal portion 18 at that end of the cover remote from the wringer 15. These marginal portions are external to and contact with the corresponding upper edge portions of the body 10 in order to maintain the cover in position and permit sliding of the same to its retracted position at the rear end of the body, as shown in Figure 3, the said rear end having side studs 19 adapted to be engaged by hooks 20 provided on the front ends of the side marginal portions 17, and by means of which the cover is supported in its retracted position.

Heretofore it has been necessary, whenever articles of clothing were to be placed in the barrel for washing or to be taken out when clean, to remove the customary heavy cover in each instance, and when removed, the opening being considerably larger than the barrel afforded constant opportunity for articles to fall into the space between the barrel and the wall of the body. Furthermore, when clothing was being passed through the wringer articles frequently fell back in like manner and it was found difficult if not impossible to recoup them without having to lift the entire barrel out of the machine.

My improved machine is designed to entirely eliminate these disadvantages, and with this end in view, I form a rectangular port 21 centrally in the cover 16 and considerably removed from its edges so that its longitudinal and lateral dimensions are appreciably less than that of the barrel. In so doing, a portion 22 of the cover, which por-

tion I have designated as a retaining apron, is left adjacent to the front of the wringer and is adapted to serve as a drain board and to catch any articles falling back from the 5 rolls of the wringer during the wringing operation. This port 21 is closed by the closure 23 of relatively light weight when compared with the large cover 16, the closure being provided with a suitable hand-hold 24 10 by which it can readily and easily be lifted to uncover the port 21 when articles of clothing are to be placed into or removed from the barrel.

The numeral 25 designates a removable 15 segmental barrel section of such dimension as to permit its removal through the port 21, and as shown in Figure 2 the section is positioned lengthwise intermediate the bridging head ends 26 and 27 of the main body portion of the barrel 12 the front end 20 27 being positioned directly under the apron portion 22 of the cover 16. Side flanges 28 are also provided to depend toward the barrel from the inner side margins of the cover.

25 It will thus be seen that while the large cover 16 may be slidably retracted to permit the cleansing of the body of the machine, yet the more frequently recurring operation of handling the clothing involves the use and 30 employment of a port opening smaller than the barrel in order to obviate loss of articles of clothing as hereinbefore more fully set out, the employment of a lighter and more portable closure member to close the port 35 and of a segmental barrel section capable of being easily raised through the port, a portion of the cover serving as a retaining apron during the passage of the clothing in the barrel and through the port to the wringer.

40 From the foregoing, the essential elements, features and operation of my improved machine, together with its simplicity and other advantages thereof, will be clearly apparent to those skilled in the art.

45 I do not desire to be understood as limiting myself to the precise details of construction and arrangement shown, as variations and modifications in the features of construction and arrangement may be made 50 without departing from the spirit and scope of my invention and improvements. I therefore reserve the right to all such variations and modifications as properly fall within the scope of my invention and the terms of the 55 following claims.

What I claim is:

1. In laundry apparatus, the combination of a washing machine body having an open

top substantially co-extensive with the length and breadth of said body, a substantially flat removable main cover for closing said open top provided with a centrally disposed port in its flat surface, a barrel for said body insertible thereinto through said open top and having an opening disposed 60 intermediate side and end portions of the same, a closure section for said opening and liftable bodily through said port, and a supplementary removable cover for said port superposed upon said main cover, the side 70 and end portions of the main cover about said port projecting inwardly from the body of the machine to extend over those side and end portions of the barrel about its opening, and one of the said end portions of the main 75 cover adapted to serve as a retaining apron, upon removal of the supplementary cover, substantially as and for the purpose set forth.

2. A washing machine comprising in combination a body formed with an open top containing a barrel provided with a segmental opening and a lid for said opening, a main cover for said body constructed to permit removal of the barrel through said 85 open top, said main cover substantially horizontally disposed in a plane above the peripheral boundary of said barrel and having a port constructed to permit removal of the lid, side and end portions of said main cover 90 extending inwardly from said body over corresponding portions of the barrel about said opening, and a supplementary portable cover for said port.

3. In laundry apparatus, the combination 95 of a washing machine body having side and end walls, a barrel longitudinally disposed in the body, said body provided with an open top disposed in a horizontal plane and through which said barrel is designed to be 100 inserted, a removable substantially flat main cover for closing said open top supported by said walls and formed with a centrally disposed port whereby to provide a retaining apron adjacent one end wall of the said 105 body, said barrel having arcuate bridging end portions and a segmental closure section intermediate said end portions and removable bodily through said port, said retaining apron extending over one of said end portions, and a supplementary removable cover 110 for the said port.

In testimony whereof I have hereunto signed my name and affixed my signature.

HALVOR H. LYCHE.
